RAILWAY-RAIL SPLICE.

945,598.

Specification of Letters Patent.

Patented Jan. 4, 1910.

Application filed October 9, 1907. Serial No. 396,620.

To all whom it may concern:

Be it known that I, ISRAEL NOAH PRENOVICH, a citizen of the United States, and a resident of the city of New York, in the county of New York and State of New York, have invented certain new and useful Improvements in Railway-Rail Splices, of which the following is a specification.

My invention relates to improvements in railway-rail splices, and the main object of my invention is, to provide a more efficient, and a more economical splice for railway rails, than heretofore used.

It is also an object of my invention to provide in connection with the splice, means for the prevention of a lateral displacement, and a longitudinal bodily creeping of the rails.

I attain my objects by the construction, illustrated in the accompanying drawing forming part of this specification, in which—

Figure 1, is an elevation of the splice, Fig. 2 a cross-section at the line 25 shown in Fig. 1 (the ends of a pair of adjacent rails, 30 and 31, are shown in fine lines). Fig. 3, is also a cross-section of the line 25 shown in Fig. 1 showing the sections of the splice-plates, as in Fig. 2, but the anchor angle-plates 18 and 19, and the locking angle-plates 13 and 20 and the flat bar 12, which are shown in Fig. 2, are omitted in Fig. 3, while there are washers 16, shown in the latter figure, which are not shown in Fig. 2. Fig. 4, is a bottom view of the splice, showing the angle plates 18 and 19 projected thereon.

Similar characters refer to similar parts throughout the several views.

The splice consists of the two plates, 1—28, and 2—23, which plates may also be used separately. An angle-plate 13 may be riveted on to the upright member of the plate 1—28, by rivets 14, as shown in Figs. 1 and 2. The outstanding leg of this angle-plate in combination with the flat bar 12, bolted to it (the holes for the bolts in question are indicated at 29, in Fig. 1), is adapted to engage the nuts 10. An angle-plate 20, shown in Fig. 2, may be similarly riveted on to the upright member of the splice-plate 2—23 (the rivets for this connection are not shown in the drawings). The outstanding leg of this angle-plate is adapted to engage the heads 11 of the bolts 9, used in the construction. The said locking angle-plates and the flat bar, have been fully described and claimed

in my application for a patent, for an improvement in railway-rail splices, filed May 29, 1907, Serial No. 376,371 (the two locking angle-plates, and the flat bar, are marked 60 there 3, 13 and 4, respectively), and I have shown in Figs. 1 and 2, how the same locking angle-plates can be used, if desired, with the splice, herein described. The plates 1—28 and 2—23, besides being connected with each other and with the webs of the rail-ends to be joined, by the bolts 9, passing also through the vertical legs of the locking angle-plates 13 and 20, if the latter are used, are interlocked with each other underneath 70 the bottoms of the rails, by means of the half dove-tail notch 24—5—28.

In the plate 1—28, the upright member 1—3, supporting at 1, the top flanges of the rails, and the oblique member 3—4, resting 75 on the inclined surfaces of the lower rail flanges, are of the ordinary fish-plate angle-plate shape. The foot member 4—28, ending with the half dovetail notch 24—5—28, is in general, also of a known form, except that 80 there is a free space 30, provided, between the top surface of the said foot-member and the bottoms of the rails, and except, that the inclined surface 5, of the half dovetail notch is made parallel to the corresponding inclined surfaces of the lower rail flanges. The half dovetail notch 24—5—28, may be omitted, in case the plate 1—28, is used separately from the plate 2—23, and the described free space 30, will in this case be the 90 only new feature of the plate 1—28. In the plate 2—23, the upright member 2—3, supporting at 2, the top flanges of the rails, and the oblique member 3—6, resting on the inclined surfaces of the lower rail flanges, are 95 exactly the same, as the members 1—3, and 3—4, of the described plate 1—28. The member 6—7—23, of the plate 2—23, is made up of the double bend 6—7, and the foot-member 7—23, the upper surface 8, of the 100 latter being parallel to, and adapted to be in contact with, the inclined surface 5, of the half dove-tail notch. The described surfaces 5 and 8, being both parallel to the corresponding inclined surfaces of the lower rail flanges, the plate 2—23 can be moved toward the central line of the rails, without affecting the tight fit between the said two surfaces, or the clearance 30, provided between the top surface of the foot member 4—28, and the 105 bottoms of the rails in any manner whatever. By moving, however, the plate 1—28, toward

the central line of the rails, the inclined surface 5, will be raised up and away, from the surface 8, and a free space (t),—the free space in question, and the reference (t), are not shown in the drawings—, will thus be provided between the said two surfaces. The surface 5, when raised up and away, from the surface 8, as described, remains always parallel to the latter, and the said two surfaces will become in contact again, after the longitudinal edge 28, of the plate 1—28, has been deflected somewhat downward, under the influence of the wheel-loads. Both free spaces, 30 and (t), must be made as small as possible, so that the rails, which are not in contact with the foot member 4—28, when not under the influence of the wheel-loads, will not have to deflect much under the latter influence, when loaded, before becoming in tight contact with the said foot-member, and by means of the latter also with the foot-member 7—23. The free space 30, is a provision, first, for small inward movements of the plate 1—28, caused by tightening up, from time to time, of the nuts 10 or 17 (the inward movements of the plate 2—23, do not affect the free space 30, as has been described before), and second, for the longitudinal sliding of the rail-ends, due to the expansion and contraction of the rails by changes in the temperature.

The wear of the metal of the rails and the splice plates, which is relatively considerable at the inclined surfaces of the rail-flanges and the adjacent surfaces of the splice plates in ordinary fish-plate splices; will evidently be small in the splice under consideration, by reason of the support afforded to the rail-bottoms, by the plates 1—28 and 2—23, when under the influence of the wheel-loads, and the consequent diversion of a part of the pressure of the wheel-loads, from the inclined surfaces of the rail-flanges and of the adjacent surfaces of the said plates, to the foot-members of the latter. The plates 1—28 and 2—23, will thus not have to be moved toward the central line of the rails, as much as in the ordinary fish-plate splices, and although each of the inward movements of the plate 1—28, is accompanied by a corresponding upward movement of the same plate, the total upward movement of the latter, and consequently the total clearance required between the top surface of the foot member 4—28, and the bottoms of the rails, is very small. The longitudinal sliding of the rail-ends due to the expansion and contraction of the rails by changes in the temperature 60 will evidently take place in the splice, herein described, in the same manner as in splices having no plate underneath the bottoms of the rails, as long as the free space 30, between the top surface of the foot member 4—28, and the bottoms of the rails, has not

been reduced to zero, by inward movements of the plate 1—28. In the extreme case where the free space 30, has been reduced to zero, as described, the foot members 7—23, and 4—28, will also not interfere with the necessary sliding of the rail-ends, the former will not interfere at all, and the latter not seriously, on account of the free space (t), provided in this case, between the inclined surfaces 5 and 8, of the foot members 4—28, and 7—23. The foot-member 7—23, is in the said extreme case, and when not under the influence of the wheel-loads, not in contact with the half dovetail notch, while the foot member 4—28, is under the same conditions, an overhang, adapted to be deflected downward, by a relatively small pressure, applied at its top surface. In order to reduce the free space (t), which is provided, between the inclined surfaces 5 and 8, of the foot-members 4—28 and 7—23, by inward movements of the plate 1—28, and to make the maximum width of the space (t), about equal to the maximum width of the free space 30 (the width of the space (t) is increasing twice as rapidly, as the width of the space 30, is decreasing, while the plate 1—28, is being moved toward the central line of the rails), I construct the plates 1—28 and 2—23, in such a way, that the foot member 7—23, of the plate 2—23, has a tight fit on the surface 5, of the half dovetail notch. By this construction, some of the inward movements of the plate 1—28, will be used up in order to annul the pressure exercised by the foot member 7—23, on the said surface 5, before the latter can be actually raised up and away from the surface 8.

The angle-plates 18 and 19, comprising each two legs, may be riveted on to the bottom of the plate 1—28, with rivets 26, counter-sunk on the side of the plate, nearest to the bottoms of the rails as shown in Figs. 2 and 4, the angle-plates are omitted in Fig. 1, so as not to crowd the drawing too much. The outstanding legs of the said angle-plates are adapted to be embedded in the ballast, and anchor the plate 1—28, in position. The angle-plates are shown in a skew in relation to the longitudinal central line of the rails, so as to make their outstanding legs better adapted to prevent both a lateral and a longitudinal displacement of the plate 1—28. The rail-ends 30 and 31, are prevented from changing their location laterally and longitudinally (except a certain longitudinal sliding of the rail-end 30, as will be described later), by being well connected with the plate 1—28, as shown in the drawings. The angle-plates 18 and 19, may be similarly riveted on to the foot member of the plate 2—23, in case the latter is used separately from the plate 1—28.

The idea of the described anchor angle-plate is new, although the general idea of fixing the splice and the rails in position, by having the splice-plates partly embedded 5 into the ballast, is old. The anchor angle-plates 18 and 19, also the locking angle-plates 20 and 13, the latter described in another place of this specification, are omitted in Fig. 3, in which figure only the parts 10 of the splice proper are illustrated.

The slotted holes 27, in the web of the rail-end 30, as dotted in Fig. 1, show the commonly used provision for the required 15 sliding of the rail-end, due to the expansion and contraction of the rail in question, by changes in the temperature. The longitudinal extreme edge 23, of the foot member 7-23, is rounded up somewhat, so as to facilitate the erection of the plate 2-23.

There is ample clearance provided at 6-7, 20 between the adjacent surfaces of the plates and the longitudinal extreme edges of the lower rail-flanges, and also between the adjacent surfaces of the two plates, at 28, and 25 between the surfaces 23 and 24, not only as a provision for certain inward movements of the plates 1-28 and 2-23, but also for small inaccuracies in the bent parts of the 30 said plates. The clearance at 4, is made especially large, in order to avoid as much as possible a tightening up of the adjacent longitudinal edges, of the lower rail flanges.

While I have shown and described only one example of the physical embodiment of 35 my invention, I do not intend to limit the scope of my invention to this specific example. I want it to be understood, that many changes may be made in the detail of the construction, without departing from 40 the principle of my invention.

I am aware, that splice-plates enveloping the lower flanges of the rails, and interlocking with each other underneath the bottoms 45 of the rails, have been used before, and I do not claim the above idea broadly. But—

What I do claim as my invention, and desire to secure by Letters Patent of the United States, is:

1. A splice-plate for railway-rails comprising integrally an upright member having holes for fastening the plate to the rails, and adapted to bear against the lower inclined surfaces of the top-flanges of the rails, an oblique member, continuous with 50 the lower edge of the upright member and adapted to bear against the upper inclined surfaces of the lower rail-flanges, and a foot-member, continuous with and turned under, the oblique member, the foot-member running 55 underneath, and parallel to, the bottom surfaces of the rails forming a free space, of a limited width, between its top surface, and the said bottom surfaces of the rails, and being adapted to be in contact 60 with the latter, when under the influence of

the passing trains, substantially as herein described.

2. The combination of a splice plate for a railway-rail joint comprising integrally an upright member adapted to bear against the lower inclined surfaces of the top flanges of the rails, an oblique member continuous with the lower edge of the upright member and adapted to bear against the upper inclined surfaces of the lower rail-flanges, and a foot- 70 member, continuous with and turned under the oblique member, the top surface of the foot member being parallel to the bottom surface of the oblique member, and angle-plates comprising each, two legs one of the 75 legs of each angle-plate being riveted on to the continuous bottom surface, unbroken throughout its length, of the foot-member of the splice-plate, and the other, outstanding leg, of each angle plate, being adapted 80 to be embedded in the ballast, substantially as herein described.

3. The splice herein described, for railway-rails, consisting in combination with the rail-ends to be joined, of two plates, secured to the rails by bolts, one of the plates comprising integrally an upright member adapted to bear against the lower inclined surfaces of the top flanges of the rails, an oblique member continuous with the lower edge 90 of the upright member, and adapted to bear against the upper, inclined, surfaces of the lower rail-flanges, and a foot-member continuous with and turned under the oblique member, the foot member running underneath and parallel to the rail-bottoms, forming 95 a free space between its top surface and the bottom surfaces of the rails, and ending with a half dove-tail notch, the inclined surface of the latter being parallel to the corresponding inclined surfaces of the lower rail-flanges, the other plate comprising integrally an upright member, adapted to bear against the lower inclined surfaces of the top flanges of the rails, an oblique member 100 continuous with the lower edge of the upright member, and adapted to bear against the upper, inclined, surfaces of the lower rail-flanges, and a foot-member continuous with and turned under the oblique member, 105 the top surface of the foot member being parallel to the bottom surface of the oblique member, and being adapted to engage the inclined surface of the half dove-tail notch, of 110 first plate, substantially as described.

4. The splice herein described for railway-rails, consisting in combination with the rail-ends to be joined, of a plate, comprising integrally an upright member adapted to bear against the lower, inclined, surfaces of the top flanges of the rails, an oblique member continuous with the lower edge of the upright member and adapted to bear against the upper, inclined, surfaces of the lower rail-flanges and a foot member continuous 115 120 125 130

with, and turned under, the oblique member, the foot member running underneath, and parallel to the rail-bottoms, forming a free space between its top surface and the 5 bottom surfaces of the rails, and ending with a half dove-tail notch, the inclined surface of the latter being parallel to the corresponding inclined surfaces of the lower rail-flanges; two angle-plates, comprising each 10 two legs, one of the legs of each angle-plate being riveted on to the bottom surface of the foot-member of the described plate, and the other, outstanding, leg of each angle-plate being adapted to be embedded in the 15 ballast; and a plate comprising integrally an upright member, adapted to bear against the lower inclined surfaces of the top flanges of the rail, an oblique member, continuous with the lower edge of the upright member, and adapted to bear against the upper inclined surfaces of the lower rail-flanges, and 20 a foot-member continuous with and turned under the oblique member, the foot member running underneath, and parallel to, the rail bottoms, forming a free space between its top surface and the bottom surfaces of the 25 rails, and angle-plates comprising each two legs, one of the legs of each angle-plate being riveted onto the bottom surface of the described foot-member of the splice-plate, and the other, outstanding, leg of each angle-plate, being adapted to be embedded in the 30 ballast, substantially as herein described.

30 5. The combination of a splice-plate for railway-rail joints, having a continuous foot-member, unbroken throughout its length, and running underneath, and parallel to, the bottom flanges of the rails, and an 35 anchor, consisting of angle-plates, compris-

ing each two legs, one of the legs of each angle-plate, being riveted on to the bottom surface of the said continuous foot member, of the splice plate, and the other, outstanding, leg of each angle-plate being adapted to be 40 embedded in the ballast, substantially as herein described.

6. The combination of a splice-plate for railway-rail joints, comprising integrally an upright member, adapted to bear against 45 the lower inclined surfaces of the top flanges of the rails, an oblique member, continuous with the lower edge of the upright member, and adapted to bear against the upper inclined surfaces of the lower rail-flanges, and 50 a foot-member continuous with and turned under the oblique member, the foot member running underneath, and parallel to, the rail bottoms, forming a free space between its top surface and the bottom surfaces of the 55 rails, and angle-plates comprising each two legs, one of the legs of each angle-plate being riveted onto the bottom surface of the described foot-member of the splice-plate, and the other, outstanding, leg of each angle- 60 plate, being adapted to be embedded in the ballast, substantially, as herein described.

Signed at New York in the county of New York and State of New York this 7th day of October A. D. 1907.
